UNITED STATES PATENT OFFICE.

OLAF ELTON, OF PORT WASHINGTON, WISCONSIN, ASSIGNOR TO GILSON MANUFACTURING COMPANY, A CORPORATION OF WISCONSIN.

SHEET-METAL HUB FOR CHAIR-IRONS.

1,316,089.

Specification of Letters Patent. Patented Sept. 16, 1919.

Application filed February 15, 1919. Serial No. 277,143.

To all whom it may concern:

Be it known that I, OLAF ELTON, a citizen of the United States, residing at Port Washington, county of Ozaukee, and State of Wisconsin, have invented certain new and useful Improvements in Sheet-Metal Hubs for Chair-Irons, of which the following is a specification.

My invention relates to improvements in sheet-metal chair-irons and has particular reference to that portion thereof commonly termed the "hub."

The principal objects of the invention are to produce a light, rigid, hub of sheet-metal, and so design the principal part thereof as will adapt it to be formed integrally and readily stamped and folded to form with but negligible waste of material.

Other minor objects of the invention will hereinafter appear, and the novel features thereof will be particularly pointed out in the appended claims.

Referring to the drawings—

Figure 1 is a side elevation of a sheet-metal chair-hub embodying my invention, the same being shown with certain of the auxiliary parts of the chair-iron in position thereon;

Fig. 2 is a radial vertical sectional view of the hub, the lower portion of the same being broken away and the auxiliary parts above referred to being omitted;

Fig. 3 is a detail in plan of the blank before bending and from which is formed the principal part of the hub; and

Fig. 4 is a transverse sectional view taken on the dotted lines 4—4 of Fig. 1.

Similar numerals of reference indicate similar parts in all the figures of the drawings.

The hub proper consists of the upper and lower annular plates 13 and 6, respectively, and the connecting side-walls 5, and central sleeve 11.

The sleeve, as is usual, carries the adjusting-standard 18, and the latter, in turn, carries the J-washer 23, and hand-wheel 19. The latter is flanged, as at 21, the flange being engaged by the goose-neck standard 22, mounted on the upper plate 13. These auxiliary parts thus referred to form no part of my invention, the latter having entirely to do with the hub proper.

In Fig. 3 of the drawing I have illustrated in detail the blank, before bending, from

which the lower plate and parts carried thereby, is formed. This lower plate, following the usual custom, is, in this instance, circular, and is provided with a central annular opening 9, which is surrounded, if desired, by an upturned narrow flange 10. From the edge of the plate radiate the side-walls 5, and these alternate with radial extensions 7, designed to extend under the chair-legs and aid in supporting the same. 60 Extensions 7 are at intervals provided with countersunk screw-receiving holes 8, the screws (not shown) extending upwardly through said holes and into the wooden chair-legs. Between the extensions 7 for supporting the legs, the side-walls 5 are bent upwardly at a right-angle to the plate 6 and upon the curved dotted lines *a* (see Fig. 3) so that in cross-section said walls are convexed or segmental in shape or disposition and therefore readily receive the upper plate 13, the edge of which, in the present instance, is annularly flanged so as to inclose the upper ends of said walls. The walls may be of any desired shape in cross-section, and so may the annular flange of the top-plate be made otherwise than annular in order to conform to such walls. The upper ends of the walls and the upper plate 13 may be secured together in any desired manner, as for instance, they may be spot-welded, or as shown in Fig. 2, each of the walls may be formed with a slot 16, to receive and interlock with a corresponding bent tongue 17, formed at intervals at the 70 lower edge of the flange of the upper plate. 80

The upper plate is further provided with a central opening 14, from which may depend a narrow flange 15, the opening and flange referred to corresponding with the 85 opening and flange, 9 and 10, respectively, mentioned in connection with the lower plate.

The sleeve 11, heretofore referred to, if employed, is preferably formed of sheet-metal, and as best illustrated in Fig. 2, its ends are flared, as at 12, to receive the flanges 10 and 15 of the bottom and upper plates respectively. If desired, the two plates and the ends of the sleeve may be 100 spot-welded. Any other convenient means may be employed for connecting the sleeve and plates, the means shown merely being a 105 suggestion.

It will be observed that the principal part 110

of the hub is the lower portion comprising the lower plate, the side-walls and the leg-supporting extensions, and that these parts are all formed integral. It will be understood that the spaces between the side-walls, when the latter are bent to their vertical positions, receive the inner ends of the usual chair-legs, and also that the spaces between the latter, usually requiring the addition of 10 filler-blocks, are closed by said side-walls, the finished hub, aside from the legs, being cylindrical by reason of the fact that the side-walls are bent upon the curved dotted lines *a*. Of course, by bending the side-walls upon straight lines instead of curved, the hub would be given an octagonal appearance. The external surfaces of the side-walls may be ornamented in any way desired, as, for instance, grained in imitation 20 of wood, and thus while the chair-base would have the appearance of being entirely of wood yet it would, as a matter of fact, be entirely of sheet-metal, with the exception of the legs, and therefore have far more 25 strength and durability and also be much lighter. The blank illustrated in Fig. 3 may be readily stamped from a strip of sheet-metal of the proper width, and the fact that very little waste will result will be 30 readily appreciated.

While I have shown and described, and prefer, to form the bottom-plate 6 with the integral side-walls 5, yet it is within the scope of my invention to form such side-walls integral with the top-plate.

Having described my invention, what I claim is:

1. A sheet-metal hub for chair-irons, the same comprising a bottom-plate having a 40 central opening, leg-supporting extensions radiating from the plate, integrally formed side-walls bent upwardly from the plate and alternating with each of the leg-supporting extensions, an upper or top-plate mounted on 45 independent of and connected to the upper ends of each of the side-walls and having an opening corresponding with that of the bottom-plate, and a sleeve connecting the openings of the two plates.

50 2. A sheet-metal hub for chair-irons, the same comprising a bottom-plate having a central opening, integrally formed side-walls spaced apart to form leg-receiving openings and bent upwardly from the plate, 55 a top-plate mounted upon and secured to the upper ends of each of the said side-walls and independent thereof and having an opening corresponding with that of the bottom-plate, and a sleeve connecting the openings of the two plates.

60 3. A sheet-metal hub for chair-irons, the same comprising a bottom plate having a central opening, integrally formed side-walls, segmental in cross-section, and spaced apart to form intermediate leg-receiving

openings, a top-plate mounted upon and secured to the upper ends of each of the side-walls independent thereof and having an opening corresponding to the central opening of the bottom-plate, and a sleeve connecting the openings of the two plates. 70

4. A sheet-metal hub for chair-irons, the same comprising a bottom-plate having a central flanged opening and surrounding integrally formed side-walls spaced apart to 75 form leg-receiving openings, a top-plate surmounting independent of and secured to each of the side-walls and provided with a central flanged opening, and a sleeve having its upper ends flared to receive the flanges of 80 and connecting the openings of the two plates.

5. A sheet-metal hub for chair-irons, the same comprising a bottom-plate having a central opening and upwardly disposed integrally formed side-walls, the latter being spaced apart to form leg-receiving openings and having their upper ends provided with mortises, a top-plate surmounting the side-walls and having a central opening corresponding to that of the bottom-plate and provided with a depending marginal flange 85 embracing said side-walls, said flange being provided with tongues bent to engage said mortises. 90

6. A sheet-metal hub for chair-irons, the same comprising a bottom-plate having a central opening, upwardly disposed integrally formed side-walls spaced apart to form intermediate leg-receiving openings, 100 and leg-supporting extensions integrally formed and extending radially from the plate coincident with said leg-receiving openings, a top-plate having a central opening aligning with that of the bottom-plate 105 and having a marginal flange embracing the upper ends of the side-walls, means for securing said top-plate in position upon the upper ends of the side-walls, and a sleeve connecting the central openings of the two 110 plates.

7. A sheet-metal hub for chair-irons, the same comprising a bottom-plate having a central opening and leg-supporting extensions radiating from the plate, an upper 115 or top-plate having a central opening, a sleeve connecting the openings of the two plates, and vertical side-walls integrally formed with one of said plates and having their ends connected to the other of said 120 plates, said side-walls being spaced apart to produce leg-receiving sockets and alternating with the leg-supporting extensions of the bottom-plate.

8. A sheet-metal hub for chair-irons, the same comprising a bottom-plate having a central opening and marginal integrally formed vertically disposed side-walls spaced apart to produce intermediate leg-receiving 125 openings, and a top-plate independent of 130

each of the side-walls and provided with a marginal depending flange embracing each of the side-walls at their upper ends, said flange conforming to the shape in cross-section of said side-walls and being connected thereto.

9. A sheet-metal hub for chair-irons, the same comprising a bottom-plate and leg-supporting extensions radiating from the plate, an upper or top-plate, vertical side-walls integrally formed with one of said plates, said side-walls alternating with the leg-supporting extensions of the lower plate

and spaced apart to form intermediate leg-receiving openings coincident with the leg-supporting extensions, and means for securing the ends of said side-walls to that plate against which they abut. 15

In testimony whereof I have signed my name to this specification in the presence of 20 two subscribing witnesses.

OLAF ELTON.
